UNITED STATES PATENT OFFICE.

SAMUEL T. SKEEN, OF CENTRALIA, ILLINOIS, ASSIGNOR OF ONE-HALF TO CHARLES E. STEAD, OF CENTRALIA, ILLINOIS.

DRILL.

Application filed September 25, 1923. Serial No. 664,666.

This invention relates to a drill particularly adapted for use in drilling into coal deposits, one of the objects being to provide a very simple and inexpensive miner's drill 5 having a blade or bit which may be easily detached from the blade-holder. The blade is preferably formed of a single piece of metal and is rigidly secured to an end portion of a long spiral stem, and since the 10 blade is a small and inexpensive article, it may be economically made of a high grade material well adapted to withstand the service to which it is subjected.

An important advantage in my drill is 15 that the drill blades, being detachable from the drill stems, may be removed and replaced by other blades whenever necessary, thereby eliminating the necessity of taking the drill stems from the mine to sharpen the blades, as is ordinarily done. Due to the fact that the wear is on the detachable blades and not 20 on the drill stems, it is apparent that a single drill stem may be used for a long period of time.

With the foregoing and other objects in 25 view, the invention comprises the novel construction, combination and arrangement of parts hereinafter more specifically described and illustrated in the accompanying drawings wherein is shown the preferred embodiment of the invention. However, it is to be 30 understood that the invention comprehends changes, variations and modifications which come within the scope of the claims hereunto appended.

Fig. I is a plan view of an end portion 35 of a drill embodying the features of my invention.

Fig. II is a horizontal section on the line 40 II—II of Fig. I.

Fig. III is a perspective view of the blade-receiving end portion of a drill.

Fig. IV is a perspective view of one of my improved blades.

In the drawing A designates a drill stem 45 in the form of a spiral conveyor having its end B flattened, as illustrated in Fig. III, said stem being provided with a slot 1 which extends longitudinally of said flattened end portion. The slot 1 is open at its outer end 50 and a circular opening 2 of greater diameter than the width of said slot is located at the inner end of said slot, said slot being in communication with said circular opening.

The blade 3 is preferably formed of a

single piece of material provided with cutting edges 4, and includes an integral counterboring blade 5. The blade 3 is provided with a bifurcated upper portion comprising a portion 6 and a portion 7, said 60 blade being bent in a manner to provide a wall 8 which extends longitudinally of said blade. The operation of bending the blade so that it assumes the shape shown most clearly in Fig. II separates the portions 6 65 and 7, one from the other, in a direction which is at right angles to the side faces of said portions 6 and 7, a distance equal to the thickness of the flattened portion B of the drill stem A. The blade 3 is provided 70 with a circular opening 9 which is approximately the same diameter as the opening 2 in the portion B of the drill stem, said opening 9 being located at the inner end of the slit 10 which separates the portions 6 and 7 75 from each other.

To assemble the drill stem A and the blade 3 of my improved drill the blade is brought to a position where the space between the portions 6 and 7 of said blade is in alinement 80 with the flattened portion of the drill stem. The blade at this time is so positioned that the slot 1 in said flattened portion B of the drill stem will be in alinement with the wall 8 of the blade. The blade 3 is then moved 85 inwardly toward the inner end of the slot 1 until the end B' of the flattened portion B of the drill stem contacts with the inner face of the wall 3' of the blade 3, which wall is so located that the circular opening 9 of the blade registers with the circular opening 2 of the drill stem.

When the drill stem and the blade have been assembled as described, a bolt 11 is passed through the registering openings 2 90 and 9 and a nut 12 is screwed on an end of said bolt. As shown in Fig. II, the seats against which the head of the bolt 11 and the nut 12 rest are equal to only approximately one-half of the width of said bolt 100 head and nut, and to provide seats sufficiently wide to produce suitable contacting faces I employ a pair of washers 13. The washers 13 are each provided with a flat portion and an inclined portion, the flat portion 105 contacting with a face of one of the portions 6 or 7 and the inclined portion contacting with an adjacent face of the flattened portion B of the drill stem A (Fig. II).

From the foregoing it is plain that the blade may be very readily attached to or detached from the stem of my improved drill, and when the blade and the drill stem are assembled as described it is apparent that said blade is very securely attached to said drill stem, for the reason that the slot 1 in the drill stem and the slit 10 of the blade are of insufficient widths to permit the passage of the bolt 11 longitudinally therethrough.

By referring to Fig. II it will be seen that when the drill is in use and is being rotated in the direction indicated by the arrow in this view, the flat inner faces of the portions 6 and 7 will be in contact with the opposite side faces of the portion B of the drill stem, thus relieving the bolt 11 of much of the strain caused by the cutting action, and said bolt merely acting to hold the blade and the drill stem together.

I claim:

1. A drill comprising a stem, a blade provided with a bifurcated portion adapted to cooperate with an end portion of said stem whereby said blade may be detachably attached to said stem, the oppositely disposed leg portions of said bifurcated portion of said blade being out of alinement with each other and flat side faces of said leg portions being in contact with the opposite side faces of said end portion of said stem, and means whereby said blade is securely held in place on said stem.

2. A drill comprising a stem having a bifurcated end portion, a blade provided with a bifurcated portion adapted to cooperate with the bifurcated portion of said stem whereby said blade may be detachably attached to said stem, the oppositely disposed leg portions of said bifurcated portion of said blade being out of alinement with each other and flat side faces of said leg portions being in contact with the opposite side faces of said end portion of said stem, and means whereby said blade is securely held in place on said stem.

3. A drill comprising a stem having an elongated opening adjacent to one of its ends, a blade provided with an elongated

opening, a portion of said stem being adapted to be inserted into the elongated opening in said blade and a portion of said blade being adapted to be inserted into the elongated opening in said stem whereby said blade may be detachably attached to said stem, the portions of said blade at the opposite sides of the elongated opening therein being out of alinement with each other and flat side faces of said portions being in contact with the opposite side faces of said end portion of said stem, and means whereby said stem and blade are retained in their assembled positions.

4. A drill comprising a stem having a flattened end portion provided with an elongated slot, a blade provided with a wall arranged at an angle to the main body of the blade adapted to pass into said slot, said blade having portions separated one from the other and adapted to contact with the opposite sides of said flattened end portion of said drill stem, said drill stem and said blade having openings adapted to register one with the other, and a fastening device adapted to be passed through said registering openings to secure said blade through said drill stem.

5. A drill comprising a stem having a flattened end portion provided with an elongated slot, a blade provided with a wall adapted to pass into said slot, said blade having portions separated one from the other to provide an elongated opening in said blade, a portion of said stem being adapted to pass into said elongated opening in said blade, and said separated portions of said blade being adapted to contact with opposite sides of said flattened portion of said stem, said blade and said stem having circular openings adapted to register with each other, said circular openings being in communication with said elongated slot in the end portion of said stem and the elongated opening in said blade, and a bolt adapted to be passed through said registering openings to secure said blade to said stem.

In testimony that I claim the foregoing I hereunto affix my signature.

SAMUEL T. SKEEN.
